UNITED STATES PATENT OFFICE.

HENRY G. CORDLEY, OF NEW YORK, N. Y.

DESIGN FOR A WATER COOLER.

Application filed March 20, 1928. Serial No. 25,927. Term of patent 14 years.

To all whom it may concern:

Be it known that I, HENRY G. CORDLEY, a citizen of the United States, residing at New York, in the county and State of New York, have invented a new, original, and ornamental Design for Water Coolers, of which the following is a specification, reference being had to the accompanying drawing, forming a part hereof.

The figure is a perspective view of a water cooler showing my new design.

I claim:

The ornamental design for a water cooler, as shown.

HENRY G. CORDLEY.
